3.—→

FIG. 3

FIG. 1 is a top plan view of a packaging container for comestibles or the like showing my new design.

FIG. 2 is a front or rear elevational view thereof.

FIG. 3 is an elevational view thereof taken from the left of FIG. 1 along line 3—3 thereof, showing a portion of the end wall of the container which is repetitive along the length of the end wall, the remainder of the end wall being cut away to show the cross-section of the rim and bottom wall of the container, the right end wall of the container being identical to the left end wall.

I claim:

The ornamental design for a packaging container for comestibles or the like, as shown and described.
